[57] CLAIM

The ornamental design for golf putter head, as shown and described.

DESCRIPTION

FIG. 1 is a rear perspective view of a golf putter head according to the preferred embodiment;

FIG. 2 is a top plan view of the putter illustrated in FIG. 1;
FIG. 3 is a right side view of the putter illustrated in FIG. 1;
FIG. 4 is a left side view of the putter illustrated in FIG. 1;
FIG. 5 is a rear view of the putter illustrated in FIG. 1;
FIG. 6 is a bottom view of the putter illustrated in FIG. 1; and,

FIG. 7 is a front view of the putter illustrated in FIG. 1.
The broken line showing of fragmented shaft is for illustrative purposes only and forms no part of the claimed design.
